[57] **ABSTRACT**

A hot gas generator includes a combustion chamber the heated gases from which drives a turbine the combustion chamber being provided with air/fuel mixture for burning therein by a compressor driven by the turbine. A second compressor is provided to supply dilution fluid in the form of an air/fuel mixture. The dilution fluid together with the heated gases leaving the combustion chamber are maintained at a speed which is higher than the flame speed and the combustion of the air/fuel mixture which constitutes the dilution fluid takes place in a second combustion chamber which includes a divergent portion whereby the velocity of the gases is reduced below the flame speed.

HOT GAS GENERATOR EMPLOYING ROTARY TURBINE

This invention relates to hot gas generators of the kind comprising a combustion chamber, a first compressor for delivering an air/fuel mixture to the combustion chamber, a second compressor for delivering dilution fluid to the combustion chamber, a turbine coupled to said compressors for driving same, said turbine being driven by the heated gases leaving said combustion chamber.

The object of the invention is to provide such a generator in a form in which for a given size of generator and a given inlet temperature, the heat release can be increased.

According to the invention in a generator of the kind specified the dilution fluid is an air/fuel mixture and there is disposed downstream of the turbine a second combustion chamber having a divergent portion, the arrangement being such that the velocity of the hot gases after the mixing of dilution fluid therewith is higher than the flame speed of the air/fuel mixture constituting the dilution fluid, the velocity of the gases entering the second combustion chamber falling therein to a velocity lower than the flame speed thereby allowing combustion of the air/fuel mixture to take place within the second combustion chamber.

One example of a hot gas generator in accordance with the invention will now be described with reference to the accompanying drawing which shows a sectional side elevation of the generator.

Referring to the drawing there is provided a first compressor 10 having an inlet 11 and an outlet 12. The inlet 11 communicates with a conduit communicating with the atmosphere and formed in the wall of the conduit is an aperture 27 through which gaseous fuel can be admitted to the air flowing to the compressor.

There is also provided a second compressor 13 having an inlet 14 and an outlet 15. The inlet 14 communicates with the atmosphere and a fuel supply nozzle 16 is disposed adjacent the inlet.

The compressors are each provided with a rotor, the rotors being mounted upon a common shaft 17 which is coupled to the rotor of a turbine 18. The turbine includes an inlet 19 and an outlet 20 which opens into a diverging combustion chamber 21.

Also provided is a combustion chamber 22 which is surrounded by a casing 23. The combustion chamber 22 at one end mounts a burner 24 and the burner is coupled to the outlet 12 of the first compressor. Projecting into the combustion chamber is an electrical ignitor 25 and the combustion chamber downstream of the burner is provided with apertures 26 through which dilution fluid from the space defined intermediate the combustion chamber 22 and its casing 23 can pass. The dilution fluid consists of air/fuel mixture derived from the outlet 15 of the first compressor. The outlet 15 for this purpose being connected to the aforesaid annular

space.

In operation, the air/fuel mixture leaving the first compressor is ignited by the ignitor 25 and burns within the combustion chamber 22. The temperature of the heated gases is reduced in known manner by the dilution fluid which enters the combustion chamber by way of the apertures 26 and the heated gases then pass through the turbine 18 into the combustion chamber 21. The heated gases leaving the combustion chamber 21 10 22 drive the turbine and this in turn drives the compressors so that once started the apparatus is self sustaining providing fuel is supplied to the burner.

In order to obtain a greater heat release fuel is mixed with the air flowing through the second compressor but 15 in order to prevent this fuel burning until it has passed through the turbine, it is arranged that the velocity of the dilution fluid and the gases leaving the combustion chamber 22 are higher than the flame speed of the air/fuel mixture constituting the dilution fluid. In view of this no combustion will take place until the gases enter the combustion chamber 21. This combustion chamber diverges and therefore the velocity of the gases falls below the flame speed. Once the velocity has fallen to a value below the flame speed spontaneous combustion takes place and the fuel which flows through the nozzle 16 burns within the combustion chamber 21.

In the manner described above a high heat release can be obtained for a given size of generator and for a given temperature of the hot gases entering the turbine, than can be achieved in the case where all the fuel is burnt within the combustion chamber 22.

Having thus described my invention what I claim as new and desire to secure by Letters Patent is:

1. A hot gas generator comprising a combustion chamber, an air/fuel mixture burner disposed in the combustion chamber, a first compressor for delivering air/fuel mixture to said burner, a second compressor for delivering air as dilution fluid to the combustion chamber for cooling the heated gases produced by the burner, a turbine coupled to said compressors for driving same, said turbine being driven by the heated gases leaving the combustion chamber, means for mixing fuel with the air flowing through said second compressor, so that the dilution fluid is an air/fuel mixture, and a second combustion chamber disposed downstream of the turbine, said second combustion chamber having a divergent portion, the generator being so arranged that the velocity of the hot gases after the mixing of the dilution fluid therewith is higher than the flame speed of the air/fuel mixture constituting the dilution fluid, the velocity of the gases entering the second combustion chamber falling therein to a velocity lower than the flame speed thereby allowing combustion of the air/fuel mixture to take place within the second combustion chamber.
